(57) **CLAIM**

The ornamental design for a watering timer housing, as shown and described.

DESCRIPTION

The watering timer housing is used to contain watering timer. The watering timer is typically used to control lawn sprinklers and drip irrigation systems for lawns and plants. FIG. 1 is a front, right side, bottom perspective view of a watering timer housing showing our new design; FIG. 2 is a front elevational view thereof; FIG. 3 is a bottom plan view thereof; FIG. 4 is a right side elevational view thereof; FIG. 5 is a left side elevation thereof; FIG. 6 is a top plan view thereof; and, FIG. 7 is a back elevational view thereof.
